(57) **CLAIM**

We claim the ornamental design for a Christmas tree ornament, as shown and described.

DESCRIPTION

FIG. 1 is a perspective view of a Christmas tree ornament showing our new design.

FIG. 2 is a left side elevational view thereof, the right side being a mirror image.

FIG. 3 is a top plan view thereof.

FIG. 4 is a bottom plan view thereof.

FIG. 5 is a cross-sectional view thereof.

FIG. 6 is a perspective view of a second embodiment of FIG. 1.

FIG. 7 is a left side elevational of FIG. 6, the right side being a mirror image.

FIG. 8 is a top plan view of FIG. 6.

FIG. 9 is a bottom plan view of FIG. 6.

FIG. 10 is a cross-sectional view of FIG. 6.

FIG. 11 is a perspective view of a third embodiment of FIG. 1.

FIG. 12 is a left side elevational view of FIG. 11, the right side being a mirror image.

FIG. 13 is a top plan view of FIG. 11.

FIG. 14 is a bottom plan view of FIG. 11.

FIG. 15 is a cross-sectional view of FIG. 11.

The solid lines of the drawings show the wire spring form of the Christmas tree ornament according to Applicants' new design.
